The ornamental design for an embossed paper product, as shown and described.

DESCRIPTION

FIG. 1 is a top plan view of an embossed paper product showing the new design. The broken lines shown along the

borders of FIG. 1 depict boundaries of the claimed design. The broken line boundaries indicate that the product has indeterminate length and width, and that the surface pattern repeats uniformly throughout the length and width of the product. The broken lines form no part of the claimed design.

FIG. 2 is a cross-sectional view of the embossed paper product shown in FIG. 1 taken along the line 2—2; and, FIG. 3 is a cross-sectional view of the embossed paper product shown in FIG. 1 taken along the line 3—3.
